THOMAS FULLBRIGHT, OF RENTIESVILLE, INDIAN TERRITORY, ASSIGNOR
OF ONE-HALF TO NATHANIEL L. PAUL, OF RENTIESVILLE, INDIAN
TERRITORY.

RAILWAY-SWITCH.

No. 826,024.

Specification of Letters Patent.

Patented July 17, 1906.

Application filed April 27, 1906. Serial No. 314,110.

To all whom it may concern:

Be it known that I, THOMAS FULLBRIGHT, a citizen of the United States, residing at Rentiesville, District 10, Indian Territory, 5 have invented a new and useful Railway-Switch, of which the following is a specification.

This invention relates to that class of railway-switches adapted to be operated from 10 approaching trains, and has for its object to improve the construction and increase the efficiency, utility, and safety of devices of this character.

With these and other objects in view, 15 which will appear as the nature of the invention is better understood, the invention consists in certain novel features of construction, as hereinafter fully described and claimed.

In the accompanying drawings, forming a 20 part of this specification, and in which corresponding parts are denoted by like designating characters, is illustrated the preferred form of the embodiment of the invention capable of carrying the same into practical operation.

In the drawings, Figure 1 is a plan view of a portion of a railway-track, including the main-line rails, the switch-rails, and the side-track rails, of the usual construction, with 25 the improved switch-operating devices applied. Fig. 2 is a side elevation, enlarged, of the switch-stand. Fig. 3 is a section on the line 3 3 of Fig. 2. Figs. 4 and 5 are views in perspective of the switch-staff-tripping plates. 30 Fig. 6 is a side elevation of the weighted switch-holding arm. Figs. 7 and 8 are views of one of the tripping devices carried upon locomotives and cars of the trains and employed to trip the switch-operating mechanisms.

The improved device may be applied to any of the ordinary switch structures in common use, either of the "stub" or "split" variety, but for the purpose of illustration is 40 shown applied to an ordinary stub-switch structure, the main-line rails being represented at 10 11, the switch-rails at 12 13, and the side-track rails at 14 15, the switch-rails being coupled at their movable ends by the usual rod 16.

The improved attachments comprise levers 17 18, pivoted at 19 20 at opposite sides of the track, preferably upon one of the ties

21, extended for that purpose, as shown. The levers 17 18 are coupled at one end by a 55 rod 22, and the lever 18 coupled by a rod 23 to the switch-bar 16, while the lever 17 is coupled to another lever 24 by a rod 25, the lever 24 pivoted at 26 to one of the ties extended for that purpose. Pivoted at 27, 60 preferably to one of the ties 21, is a lever 28, coupled at 29 to the lever-coupling rod 22. Pivoted at 30 is another lever 31, coupled at one end at 32 to the free end of the lever 28. Located at a suitable distance from the 65 switch-rails, at one side of the same, is a bar 33, mounted for movement transversely of the track, as by bearings 34, and provided with trip-plates 35 36, either inside or outside the rails, as may be preferred, but perfectly 70 outside the rails, as shown. The trip-plates are formed with outwardly-curving ends and arranged so that when one trip-plate is spaced from one rail the other trip-plate will be relatively close to the other rail, as shown in Fig. 75 1. The bar 33 is coupled by a rod 37 to a bell-crank 38, and this bell-crank is coupled by a rod 39 to another bell-crank 40, coupled at 41 relatively near the lever 24, the bell-crank 40 being coupled by a rod 42 to the lever 24. Located at a suitable distance from the switch-rails, at the opposite side of the same, is a bar 43, movably connected by 80 hangers 44 to one of the ties 21 and provided with trip-plates 45 46, the bar 43 and its trip-85 plates 45 46 corresponding in construction to the bar 33 and its trip-plates 35 36. The bar 43 is connected by a rod 47 to a bell-crank 48, the latter pivoted at 49 and connected by a rod 50 to another bell-crank 51, pivoted at 90 52, and in its turn connected by a rod 53 to the free end of the lever 31. The bar 43 is associated with the main-line rails 10 11, and likewise associated with the side-track rails 14 15 is a bar 54, movable through hangers 95 55 56 and provided with curved trip-plates 57 58. The three bars 33, 43, and 54 are substantially alike and operating in the same manner. The bar 54 is coupled by a rod 59 to a bell-crank 60 and the latter pivoted at 100 61 to one of the ties and connected by a rod 62 to a bell-crank 63, the latter in turn pivoted at 64 and connected by a rod 65 to the joint 32 between the levers 28 and 31. By this arrangement it will be obvious that 105 when the trip-plates 57 58 are actuated the

switch-rails will be thrown in the same manner as the other trip-plates are operated.

The locomotives, coaches, freight-cars, cabooses, or other rolling-stock will be provided with means under the control of the train operatives for actuating the trip-plates as required.

The trip-operating mechanism consists of a flanged wheel 66, mounted for rotation upon 10 a swinging arm 67, the latter connected to the locomotive or other portion of the train and provided with means whereby it may be elevated or depressed to cause it to contact with the trip-bars when required. The arms 15 67 are under the control of the engineer, conductor, or other member of the train-crew.

With an apparatus thus described associated with the switch mechanism the engineer or other operative of an approaching 20 train by depressing one of the operating mechanisms 66 causes the same to engage one of the trip-plates, and thus throws the switch into any position he may desire. For instance, if a train is approaching on the main 25 line and the engineer desires to run his train upon the side track, he depresses the member 66, which when depressed will actuate the trip member 36, and thus cause the switch-rails 12 13 to be operated to close the side- 30 track rails through the action of the bell-crank 38 40, rods 39 42, lever 24, rod 25, lever 17, rod 22, lever 18, and rod 23. If the approaching train is to be continued on the main line and the engineer discovers that the 35 trip-plates 35 36 are in the position shown in Fig. 1, he pays no attention to the tripping mechanism carried by the train, but proceeds on his way. If the engineer discovers that the trip-plates 35 36 are in the reversed 40 position from that shown in Fig. 1 and he desires to proceed on the main line, he actuates the member 66, which is arranged to operate the trip-plate 35, and thus throws the switch over for the main line through the same 45 means just described, as will be obvious. If the engineer is approaching from the opposite direction on the main line, he can readily throw the switch into any position required by simply actuating the members 66 to 50 cause them to contact with the trip-plates 45 or 46, as the case may be. If the train is approaching on the side track, the switch is thrown by the operating trip-plates 57 or 58, as the case may be. The train operatives 55 can thus manipulate the switch in any desired manner and when approaching from either direction. The trip-plates being curved at both ends, as shown, can be operated from either side, so that after a train 60 passes through the switch the train operatives can return the switch to its former position by simply operating the device 66, which is located upon the rear end of the train, and thus operate the switch in the 65 reverse order.

Pivoted at 68 upon a standard 69 is a lever 70, having a relatively heavy weight 71 at its upper end and movably coupled by a link 72 to the rod 25, the weighted lever 70 being so arranged that when the switch is in open 70 position the gravity of the weight on the lever will operate to hold it yieldably in open position, and when the switch is in closed position the movement of the switch mechanism will automatically reverse the position of the 75 lever 70 and cause the weight 71 to hold the switch yieldably in closed position. Located adjacent to the switch-rails, preferably at the side opposite from the weighted lever 70 71, is a switch-stand 73, having a vertical 80 staff 74. The switch-stand 73 is provided with spaced recesses 75 76, into which a stop-arm 77 is caused to be alternately engaged as the staff is actuated. Extending from the staff 74 is a target-rod 78, having a target 79 85 of the ordinary form. The recesses 75 76 are so located relative to the arm 77 that when the latter is in one of the recesses the target 79 is disposed parallel with the main-line rails, and when the arm 77 is in the other recess 90 the target is disposed transversely of the main line, the switch-rails being so arranged relative to the staff 74 that the target will be in its parallel position when the switch is set for the main line and in its transverse 95 position when the switch is set for the side track. The staff 74 is arranged to be rotated in the stand 73 and also arranged to be moved vertically therein, the stop-arm 77 having its outer end extending downwardly 100 into the recesses 75 76, and can be released only when elevated, and an approved mechanism whereby the staff is elevated to release the arm 77 before it is rotated to operate the switch is illustrated in Figs. 1, 2, 3, 4, and 5 105 and is described as follows: Attached to the base of the stand 73 is a disk 80, having spaced depressions 81 with inclined sides 82, and rotatively disposed upon the staff is another disk 83, having spaced ribs 84, corresponding to the recesses 81 of the disk 80, and with inclined sides 85, corresponding to the inclined sides 82 of the recesses 81. The plates 80 and 83 are superimposed, and when in one position the ribs 84 bear in the recess 81 and when in another position the ribs 84 bear upon the "lands" of the disk 80 between the recesses 81. The staff 74 is provided with a collar 86, fast thereon and beneath which the disk 83 bears, so that when the disk 83 is elevated it 110 will carry the staff with it, while at the same time leaving the staff free to be rotated, as hereinafter explained. The disks 80 and 83 are so arranged relative to the arm 77 that when the ribs 84 are in one position relative to the recesses 81 the arm 77 will bear in the recess 76, and when the ribs 84 are in another position relative to the recesses 81 the arm 77 will bear in the recess 75, as hereinafter 115 explained. The staff 74 extends below the 120 125 130

base of the stand 73 and is provided with an arm 87, having a concentric slot 88, and the disk 83 is provided with an arm 89, from which a pin 90 extends downwardly through 5 the slot 88 and connected at the lower end to the switch-rod 16 by a rod 93. The swinging movement of the staff 74 is equal to one-fourth of a circle, in order to properly operate the target, and the length of the slot 88 10 is sufficient to cause the disk 83 to be rotated to a sufficient extent to transfer the ribs 84 to the lands between the recesses 81 of the disk 80, and thus elevate the staff 74 to release the arm 77 from the recess in the stand 73 with 15 which for the time being it is engaged, and then as the motion of the staff continues the pin 90 picks up the arm 87 and completes the movement, the ribs 84 entering the recesses 81 in the disk 80 at the end of the 20 stroke, and thus permitting the arm 77 to enter the other recess in the staff and locking the switch. By this arrangement it will be obvious that the switch is locked in both of its two positions and automatically released 25 by the action of the tripping mechanism heretofore described.

The arm 77 is formed with an intermediate joint 91 and extended into a handle 92 to enable the switch to be operated manually when 30 required, and when the switch is thus to be manually operated the rod 23 is disconnected to release the tripping mechanism.

The device is readily applicable to any of the switch structures in common use, as 35 above noted, without change therein.

The improved apparatus may be applied at any distance from the switch-rails and may be coupled by rods, chains, wire cables, or the like.

40 Having thus described the invention, what is claimed as new is—

1. In a railway-switch, the track structure including the main-line rails the side-track rails and the switch-rails, with the switch-rails coupled at their movable ends, swinging levers disposed at opposite sides of said track, a vertically-swinging bar having a weight at its upper end, a rod connecting said levers at one end, a rod connecting said switch-rails to 45 the opposite end of one of said levers, a rod connecting said weighted bar with the opposite end of said lever, and means operative by the approaching train for actuating said lever connecting-rod to cause the operation of 50 the switch in advance of the train.

2. In a railway-switch, the track structure including the main-line rails the side-track rails and the switch-rails, with the switch-rails coupled at their movable ends, swinging 55 levers disposed at opposite sides of said track, a vertically-swinging bar having a

weight at its upper end, a switch-stand having a signal-target, a rod connecting said levers at one end, a rod connecting said switch-rails to the opposite end of one of said levers, 65 a rod connecting said weighted bar with the opposite end of said other lever, a rod connecting said switch-rails with said target-operating mechanism, and means operative by the approaching train for actuating said lever-connecting rod to cause the operation of 70 the switch in advance of the train.

3. In a railway-switch, the track structure including the main-line rails the side-track rails and the switch-rails, with the switch-rails coupled at their movable ends, swinging levers disposed at opposite sides of said track, a vertically-swinging bar having a weight at its upper end, a switch-stand having spaced radial recesses, a staff movable rotatively 80 and longitudinally in said stand and provided with an arm for alternate engagement with said recesses, connecting means between said levers at one end, connecting means between said switch-rails and the opposite end of one 85 of said levers, connecting means between said weighted bar and the opposite end of said other lever, and means operative by the approaching train for actuating said lever-connecting means to cause the operation of the 90 switch in advance of the train.

4. In a railway-switch, the track structure including the main-line rails the side-track rails and the switch-rails, with the switch-rails coupled at their movable ends, swinging 95 levers disposed at opposite sides of said track, a vertically-swinging bar having a weight at its upper end, a switch-stand, a staff having spaced radial recesses and movable rotatively and longitudinally in said stand and 100 provided with a locking-arm for alternate engagement with said recesses, connecting means between said levers at one end, connecting means between said switch-rail and the opposite end of one of said levers, connecting means between said weighted bar and the opposite end of said other lever, connecting means between said staff and switch-rails, means operative by the approaching 105 train for operating said lever-connecting means to cause the operation of the switch in advance of the train, and means whereby said staff is moved upwardly to release said locking-arm at the first movement of the switch-rail-operating means. 110

In testimony that I claim the foregoing as my own I have hereto affixed my signature in the presence of two witnesses.

THOMAS FULLBRIGHT.
